UNITED STATES PATENT OFFICE.

FRANCIS HARLEY DAVIS, OF NEW YORK, N. Y., ASSIGNOR TO THE DAVIS
CALYX DRILL COMPANY, OF SAME PLACE.

TURNUCKLE.

SPECIFICATION forming part of Letters Patent No. 634,431, dated October 3, 1899.

Application filed May 15, 1899. Serial No. 716,903. (No model.)

To all whom it may concern:

Be it known that I, FRANCIS HARLEY DAVIS, engineer, of the city of New York, in the county of New York and State of New York, have invented certain new and useful Improvements in Turnuckles; and I do hereby declare the following to be a full, clear, and exact description of the invention, such as will enable others skilled in the art to which it applies to make and use the same.

My invention relates to an improvement in turnuckles, the object of the invention being to provide a turnbuckle which can be folded, and hence will permit the truss-rod with the turnbuckle thereon to be folded into a small space for shipment.

A further object is to provide a turnbuckle which will act as a universal joint and no matter how slack will still allow the apparatus to turn freely, adjusting itself while.

A further object is to provide a turnbuckle which will permit of a great adjustment of the truss-rod.

A further object is to provide a turnbuckle which will be extremely simple in construction, cheap to manufacture, strong and durable, and most effectual when in use.

With these objects in view the invention consists in certain novel features of construction and combinations and arrangements of parts, as will be more fully hereinafter described, and pointed out in the claims.

In the accompanying drawings, Figure 1 is a view illustrating my improvements, and Fig. 2 is a view in section of same.

My improved turnbuckle comprises three links 1, 2, and 3. The end links 1 and 3 are enlarged at their outer ends, as shown at 4,

and are provided with screw-threaded holes or openings 5 for the reception of screw-threaded truss-rods 6, as shown.

It will be seen that my improved turnbuckle can be placed in position on the truss-rod and the whole device shipped as one piece, as the central link 2 will permit the turnbuckle and rod to be folded in a small space and occupy no more room than the truss-rod alone.

Various slight changes might be resorted to in the general form and arrangement of the several parts described without departing from the spirit and scope of my invention, and hence I would have it understood that I do not wish to limit myself to the precise details set forth, but consider myself at liberty to make such slight changes and alterations as fairly fall within the spirit and scope of my invention.

Having fully described my invention, what I claim as new, and desire to secure by Letters Patent, is—

1. As an article of manufacture, a turnbuckle comprising three links the end links having screw-threaded holes therein for the reception of rods.

2. As an article of manufacture, a turnbuckle comprising a link, a link connected at each end of said first-mentioned link, enlargements on said last-mentioned links having screw-threaded holes or openings therein.

In testimony whereof I have signed this specification in the presence of two subscribing witnesses.

FRANCIS HARLEY DAVIS.
